UNITED STATES PATENT OFFICE.

ANTON MAYER, OF CHICAGO, ILLINOIS.

CONTROLLING MECHANISM FOR AIRSHIPS.

1,120,957.

Specification of Letters Patent.

Patented Dec. 15, 1914.

Application filed October 24, 1913. Serial No. 797,009.

To all whom it may concern:

Be it known that I, ANTON MAYER, subject of the Emperor of Germany, residing at Chicago, in the county of Cook and State 5 of Illinois, have invented certain new and useful Improvements in Controlling Mechanism for Airships; and I do hereby declare the following to be a full, clear, and exact description of the invention, such as will 10 enable others skilled in the art to which it appertains to make and use the same.

My invention relates to controlling mechanisms for airships, and more particularly to means for simultaneously controlling the 15 positions of the various movable planes of an aeroplane. In airships of this general class it has heretofore been customary to provide either a manually operated steering wheel, or a lever operated with the feet, 20 for controlling the rudder or rudder planes; and to provide separate levers for controlling the elevating and depressing planes and the tilting planes respectively. In practical 25 operation it has been found difficult for the average operator to manipulate the three sets of controls harmoniously under all conditions, and particularly so as the aviator is often exposed to such low temperatures as to 30 numb his arms and legs and thereby make it difficult for him to use his limbs with their normal freedom. Moreover, it has been found difficult in practice to prevent inexperienced persons from becoming confused in the handling of the various levers or 35 wheels, or likewise to prevent confusion on the part of experienced aviators in unexpected emergencies.

The prime object of my invention is to provide a controlling mechanism in which 40 a single manually grasped controlling member will actuate all three sets of the controlling planes, and in which the operator can instantly discern from the position of the said controlling member what its action 45 upon the controlling planes will be.

Another object is to provide simple means for holding the said single controlling member in any position to which it may have been manually moved and to provide simple 50 means for protecting the connections between the said controlling member and the movable planes so as to guard the said members against mechanical injury.

Other objects will be apparent from the

following description and from the accompanying drawings in which:

Figure —1— is a perspective view of the controlling planes of an aeroplane and of the mechanism of my invention as attached thereto, other portions of the aeroplane being either omitted or merely indicated in dotted lines. Fig. —2— is a fragmentary longitudinal section through the controlling mechanism of Fig. —1—. Fig. —3— is a plan view of the portions shown in Fig. —2—. Fig. —4— is a fragmentary view showing an alternative arrangement of the connections between the controlling member and the elevating and depressing planes.

Fig. —1— shows an aeroplane 1 equipped at its forward and rear ends with tilting planes 2 and 2' pivoted respectively upon shafts 3 and 3' and each having at their ends cross-bars 4 and 4', likewise the aeroplane has at its lateral edges pivoted planes 5 mounted upon pivots 6 and rigidly secured to cross-bars 7, and also has at its rear end a rudder 8 pivoted upon a shaft 9 and secured to a cross-bar 10. Mounted longitudinally of the airship is a pipe 11 having at 70 its forward end an extension pipe 12 which extension pipe is rotatable with respect to the said pipe 11. Mounted upon the said extension pipe 12 is a substantially U-shaped frame 13 having slots both in its vertical 75 arms and in its horizontal arm, and having a pair of pulleys 14 mounted within the said slotted vertical arms. Mounted within the extension pipe 12 midway between slotted vertical arms 15 of the frame 13 is a shaft 16 80 having a toothed wheel 17 integral therewith, and having a portion 8 extending through the upper wall of the said sleeve 12. Secured to the said extension 18 by a universal joint 19 is a steering shaft 20 extending through the slotted upper end of the member 13 and carrying at its upper end a steering wheel 21. The teeth of the wheel 17 are intermeshed with links of a relatively short chain 22 secured at its ends to cords 100 23 leading over guide pulleys 24 and connected to respectively to the opposite ends of the cross-bar 10 controlling the rudder 8. The steering post 20 is equipped between the said coupling 19 and the hand-wheel 31 with 105 a sleeve 25 swiveled upon the said steering post but immovable longitudinally thereof, which sleeve is connected to the ends of cords

26 and 27 leading respectively to ends of the cross-bars 4 and 4' controlling the forward and rear elevating and depressing planes respectively. The other ends of the 5 said cross-bars 4 and 4' are connected to each other by a cord 28, both of the said cords 27 and 28 being guided by pulleys 24 and extended through the sleeve 12 and pipe 11, which pipe and sleeve serve as a mechanical 10 protection for the said cord. Mounted in the horizontal slot in the upper portion of the frame 13 is a friction member 29 of spring bronze or other suitable material, which friction member bears continually 15 against one edge of the steering post 20 and presses the opposed edge of the said post with considerable force against the opposed wall of the said slot. Being thus held between the said friction member and the 20 opposed wall of the slot, the steering post is not movable laterally of the vehicle with respect to the frame 13, but will rotate the said frame with it about the axis of the pipe when the post is rocked or tilted from the 25 normal vertical position in which it is shown in Fig. —1— to a position in which it makes an oblique angle with the axis of the pipe 11, and shown in dotted lines in Fig. —1—. Consequently, the frame 13 may readily be 30 rocked about the axis of the pipe 11 by tilting the steering post in either lateral direction, the said rocking being permitted by the said swiveled connection between the sleeve 12 and pipe 11 and by the universal joint 35 19 interposed between the shaft 16 and the steering post 20. One end of the frame 13 is connected by cords 30 and 31 respectively, with one end of the cross-bars 7 and 7' controlling the tilting planes 5 disposed at lateral 40 edges of the airship, the other ends of the said cross-bars being connected by a cord 32. All of the said cords are normally taut and guided over pulleys 24 to permit a free motion of the cords, hence it will be evident 45 from Fig. —1— that a rocking of the frame 13 about the pipe 11 will move the said cords to actuate the said tilting planes. To prevent the frame from flopping loosely about its said pivotal mounting it is 50 equipped at one end with a friction member 33 bearing against a rod 34 upon the framework of the machine, the engagement between the said friction member and rod being sufficiently forcible to hold the frame 55 13 in any position to which it may have been manually moved by tilting of the steering post 20.

It will be evident from the above that the 60 aviator, who is preferably seated upon a conveniently placed chair such as the one shown in dotted lines at 35, is only required to manipulate a single operating member, namely, a steering post terminating in a steering wheel, and by rotating said wheel 65 in either direction he will correspondingly

move the rudder plane of the airship while the forward or backward movement of the steering post longitudinally of the airship will cause the cords 26, 27 and 28 to either elevate or depress the 70 airship according to the direction in which the said steering post was tilted. Likewise a lateral tilting of the steering post and the consequent rocking of the frame 13 with respect to the axis of the pipe 75 11 will cause the cords 30, 31 and 32 to actuate the tilting planes 5. It will be evident that all three of these motions can readily be combined and that the position of the steering post and steering wheel at 80 any moment will indicate at a glance the change or changes in direction which will be produced by the corresponding setting of the various pivoted planes; also that the friction members 29 and 33 will readily 85 hold the steering post in any position to which it may have been moved, thereby permitting the aviator to release his hold upon the steering wheel if he so desires. It will also be evident that the pipe or guide tube 90 11 will protect the cords running to the rear of the airship, so that they will not be exposed to the danger of breakage by contact with other objects as has heretofore commonly been the case. However, I do not 95 wish to be limited to this use of a guide tube in connection with a steering post mounted upon a universal coupling and controlling the several sets of guide planes. Neither do I wish to be limited to the exact details of 100 other portions of the construction herein disclosed as the same might be modified in many ways without departing from the spirit of my invention. For example, instead of guiding the ends of the cords 27 105 over pulleys 14 mounted in slotted vertical arms of the frame member 13, I can dispense with the said pulleys by attaching arms 36 to the swivel sleeve 25 and securing the ends of the said cords to the respective 110 ends of the said arms, as shown in Fig. —4—. Moreover, it will be evident that my invention may be applied to an airship having any desired number of controlling planes, since the control of the elevating 115 planes 2 or 2' would be effected just as readily if either one or the other thereof were omitted.

I claim as my invention:—

1. In a controlling mechanism for an air 120 ship equipped at its forward and rear ends with coacting pivoted planes, cross-bars controlling the said planes, cords connecting the cross-bars upon the respective coacting planes, a guide tube extending longitudinally of the air ship and housing the main portion of the said cords, a portion of the said tube being rotatable with respect to the remainder of said tube; and manually operable means carried by the said rotatable 130

- portion of the tube and connected to the said cords.
2. In a controlling mechanism for an air ship equipped with a plurality of planes, 5 cords connected to the said planes and respectively controlling the positions thereof, a wheel intermeshed with one of the said cords, a steering post flexibly coupled to the said wheel, a member rotatable about an 10 axis adjacent to the said flexible coupling and equipped with a slot through which the said steering post extends, the said steering post being movable about its said flexible coupling longitudinally of the said slot; 15 connections between the said steering post and the cords leading to one of the said planes, and connections between the said member and another of the said planes, and a friction member disposed transversely of 20 the axis of rotation of the said member and engaging an end of the latter and adapted by its said frictional engagement to lock the said member in any position.
3. In an air ship, controlling mechanism 25 for cords leading to the respective planes thereof, including a rotatable pipe, a shaft

mounted transversely thereof and extending through the upper wall of the said pipe, a wheel rigidly secured to the said shaft within the said pipe and intermeshing with one 30 on the said cords; a steering shaft normally in alinement with the said shaft, a universal joint connecting the two shafts, a frame rigidly mounted upon the rotatable pipe and equipped with a slot extending substantially 35 parallel to the said pipe, the said steering shaft projecting through the said slot and connected to one of the said cords, the said frame connected to another of the said cords; and a friction member extending 40 transversely of the said pipe and steering shaft and frictionally engaging a portion of the said frame to prevent accidental displacement of the latter.

In testimony whereof I have signed my 45 name in presence of two subscribing witnesses.

ANTON MAYER.
